CLAIM

The ornamental design for a wearable hummingbird feeder ring, as shown and described.

DESCRIPTION

FIG. 1 is an in use perspective view of a wearable hummingbird feeder ring according to the present design, shown worn on a person's hand.

FIG. 2 is a top perspective view of the wearable hummingbird feeder ring of FIG. 1.

FIG. 3 is an exploded top perspective view of the wearable hummingbird feeder ring of FIG. 1.

FIG. 4 is a bottom perspective view of the wearable hummingbird feeder ring of FIG. 1.

FIG. 5 is an exploded bottom perspective view of the wearable hummingbird feeder ring of FIG. 1.

FIG. 6 is a side view of the wearable hummingbird feeder ring of FIG. 1.

FIG. 7 is a front view of the wearable hummingbird feeder ring of FIG. 1.

FIG. 8 is a bottom view of the wearable hummingbird feeder ring of FIG. 1; and,

FIG. 9 is a top view of the wearable hummingbird feeder ring of FIG. 1.

The environmental broken line showing of a hand in FIG. 1 is for illustrative purposes only and forms no part of the design claim.
